UNITED STATES PATENT OFFICE.

GEORGE H. MATCHETT, OF CLEVELAND, OHIO.

COIN-CONTROL MECHANISM.

Application filed September 26, 1919. Serial No. 326,640.

To all whom it may concern:

Be it known that I, GEORGE H. MATCHETT, a citizen of the United States, residing at Cleveland, in the county of Cuyahoga and 5 State of Ohio, have invented a certain new and useful Improvement in Coin-Control Mechanism, of which the following is a full, clear, and exact description.

The present invention relates to a coin 10 controlled mechanism, which is particularly adapted for use in connection with machines for vending various articles or commodities. The invention is particularly directed to a construction which may be so adjusted 15 as to be operable upon the insertion of one or more coins.

A further object is to provide a coin guide or trackway, having a portion thereof which forms a coin receiving well, together with 20 means whereby the depth of the well may be adjusted, or in other words, its coin receiving and retaining depth and capacity may be varied so as to make the mechanism operable upon the insertion of one, two or 25 more coins.

A further object of the invention is to provide a construction of the character described, which is robust in nature and not easily broken or put out of order by the 30 repeated using and rough usage to which mechanism of this kind is subjected when in use.

Other objects of the invention will appear 35 more at large as the description proceeds and generally speaking, the invention may be said to comprise the elements and the combinations thereof set forth in the accompanying claims.

Reference should be had to the accompanying 40 drawings forming a part of this specification in which Fig. 1 is a front elevation of the mechanism forming the subject matter of this invention; Fig. 2 is an end elevation; Fig. 3 is a top plan view; Fig. 4 is a plan view partly in section showing 45 a detail of construction; and Fig. 5 is a top plan view of a part of the mechanism.

The mechanism which is shown and 50 described herein is of that class which is intended to be used in connection with the vending of various commodities and articles wherein the operating mechanism of the vending machine itself is retained in inoperative position, until by the insertion of

a proper coin or coins, the vending mechanism is in position for operation.

In many instances, a vending machine may be operated by the insertion of a single coin, but it frequently is necessary in vending an article or commodity, to require the 60 insertion of more than one coin, as for instance where the article being vended is sold at two, three or four cents, or at twenty or thirty cents. Under these circumstances the 65 mechanism which operates the vending machine should not be in operative position until the proper number of coins of the necessary denomination have been deposited in the slot.

Furthermore, a mechanism of this character, in order to be of its greatest use should 70 be so constructed that the number of coins required to operate the mechanism may be changed, thereby permitting an adjustability in this respect, which permits the same 75 mechanism to be used in connection with a varying number of coins.

Referring to the drawings, 1 indicates a suitable support which may conveniently be 80 a portion of the casing or other construction of the vending device in connection with which the coin controlled mechanism is used. This support or wall has a shaft 2 journaled 85 therein, which shaft is connected with the operating mechanism of the vending machine proper. Upon this shaft there is a tooth wheel indicated at 3. The teeth of this wheel 3 being engaged by a dog 4, which prevents the rotation of the wheel 3 in one direction. The shaft 2 may conveniently be 90 operated by the handle 5 which extends upon the outside of the casing of the vending machine. In the present instance a handle is merely suggestive of an operating means for the shaft 2, and as will be apparent, 95 other means of operating the shaft 2 may be employed than that herein described and shown.

Upon the same shaft 2 is an annular member 6, this annular member lying adjacent 100 the wheel 3. This annular member is provided with a notch 7 on the peripheral surface thereof, which notch is adapted to be engaged by the nose of a latch member 8. The direction in which the notch 7 is formed in 105 the member 6 is such as to oppose rotary motion in the direction opposite to that opposed by the dog 4 so that when the dog 4

and the latch 8 are in their engaging positions, the shaft 2 is locked against rotation.

The wall member 1 carries brackets 9 and 10^a, and in these brackets there are slidably supported the rods 10 and 11. The rod 10 carries the latch 8 and movement of the rod 10 moves the latch 8. This rod is normally under the retractive force of a spring 12, the pull of the spring being in a direction to hold the latch 8 in its engaging position with respect to the notch 7.

Mounted upon and secured to the shaft 10 is a housing 13, through which extends a rod or shaft 14, as will be later explained.

15 This housing carried by the rod 10 extends rearwardly from the shaft and the rear portion thereof forms an abutment, such as indicated at 15, adapted to be engaged by a coin as will be later described.

20 Upon the rod 11 there is a spring 16, which at one end bears against the bracket portion 9 and at its opposite end engages with a pin 17, which is carried by the rod 11. This spring normally urges the rod 11

25 away from the bracket 9. The rod 11 adjacent the opposite end is provided with a member 18, which is secured to the rod and normally under the action of the spring 16, the member 18 abuts against the bracket member 10^a.

30 The coin chute or guide way, is indicated at 20. The chute may be formed in any desired manner, but in any event there is a portion such as indicated at 20^a, which extends at substantially right angles with respect to the rods 10 and 11. The chute at the portion adjacent to the stop 18 is open at the front and rear thereof, so that the stop 18 may move transversely of the chute and push the coin which may be in front of

35 the stop 18, against the abutment 15 formed on the member 13.

The portion 20^a of the coin chute or track way, may be extended to any desired extent so that it will be available to hold substantially any desired number of coins.

40 The portion of the track way 20^a is provided with a series of aligned notches, such as indicated at 21, 22, 23, 24, 25, 26 and 27. These notches extend into the track way so

45 that in the event any one of these notches is occupied by a projection or obstruction of any character, the coin which engages the stop or obstruction will be held and coins subsequently inserted will build up within the portion 20^a of the coin chute, and if there are a sufficient number of coins to build up, so that there is a coin lying between the stop 18 and the abutment 15, then the mechanism may be operated, but not otherwise.

50 For instance, if there is a projection inserted in the opening 21, it would require but one coin to place the mechanism in operative condition. If a stop be placed in the opening 22, as shown in the drawing in Fig. 1, two coins would be necessary, if a stop be

placed in the opening 23, three coins would be necessary, and so on. Evidently the length of the member 20^a may be extended as desired, and there may be as many notches as desired.

70 It will be apparent that if it be desired to manufacture a mechanism which shall be operated upon a fixed number of coins and without any features of adjustability, the length of the chute 20^a need not be greater than the required length to accommodate the inserted coins, and in this case the notch and projection can be placed at the lower part of the chute.

75 However, in the present instance, it is desired to make the chute of proper length to provide a plurality of openings in the tube together with a plurality of stops for co-operation with the openings in the chute, so that at will the relationship between the 80 stops and the coin chute may be altered thereby in the same machine, making provision which will adapt the machine to be used with one or more coins.

85 In the present instance, upon the shaft 14 there are provided a number of projections, such as indicated at 14^a. In the present instance, there are 8 such projections, and they are spaced apart an equal angular amount; however, the stops are distributed along the 90 shaft 14 so that in effect the members 14^a are in spiral arrangement. By rotating the rod 14 to the desired degree, any desired stop 14^a may be brought into registry with its opening in the coin chute, at which time 95 all other stop members are all out of registry. The rod 14 at its upper end is provided with a pin or index member, such as indicated at 28, which in the present instance is made so that it may engage in notches such as indicated at 13^a in Fig. 1 in the upper surface of the member 13. The member 13 may be provided with a dial plate, such as indicated at 29, and is shown in Fig. 5, so that when the pin 28 is positioned properly with respect to the dial plate, the proper stop on the shaft 14 is inserted in the slot of the coin chute.

100 Extending inwardly from the member 6 is a pin 30, which pin lies adjacent the pin 17, carried by the rod 10; therefore when the member 6 is free to turn, the pin 30 will engage with the pin 17 and so move the rod 10 in a forward direction. The rod 10 is under the circumstances, coupled to the rod 11, due to the fact of the coin lying between the stop 18 and the abutment 15, so that both rods 10 and 11 move forward at the same time. As the rod 10 moves forward, it carries with it the latch member 8, so that the member 6 is free to rotate. In a very short interval of time, after the pins 17 and 30 have engaged, they are released from engagement, due to the rotative movement 115 of the member 6, whereupon the rod 11 is

released and under the action of the spring 16 is returned to initial position. The latch member 8 engages with the periphery of the member 6, but in the period of time 5 just elapsed, the latch has released the member 6, and engages with the annular periphery, which is smooth and unnotched, except at the one place here described; therefore the member 6 may continue its rotation 10 through a complete revolution of the shaft 2 and after the complete revolution, the latch 8 drops into the notch 7, thereby arresting further movement of the member 6.

When the rods 10 and 11 move forward, 15 as heretofore described, the member 13 which carries the shaft 14, moves forward with the rods so that the particular stop on the shaft 14 which was in proper relation to extend into the coin chute is carried forward, and the coins which had been retained by the stop are released and they drop through the coin chute into some suitable receptacle not shown. Therefore it will be seen that at each operation of the 20 machine the coin chute clears itself and even if there be an excess of coins over that necessary to operate the machine, all these coins pass through the coin chute.

Having described my invention, I claim: 30 1. In a device of the character described, the combination with an actuating member, a locking member therefor, a movable member adapted to be operatively connected with said locking member by the interposition of a coin, a coin trackway, a portion of said trackway being provided with a plurality of openings, a member provided with a plurality of stops, said member mounted so that any one of said stops may be presented 35 to a corresponding opening in the coin trackway, said member carrying the stops being movably mounted and movable when the aforesaid movable member is moved.

2. In a device of the character described, 45 an actuating member, a movable member associated with said actuating member, a stop carried by said movable member, a second movable member, a latch carried by said second movable member adapted in one position to restrain movement of the actuating member, an abutment carried by the said second movable member, a coin trackway positioned to conduct a coin between the said stop and the said abutment, said trackway 50 having a portion which depends below the said stop and abutment, the said depending portion of the trackway having a movable stop member associated therewith, thereby limiting the passage of a coin through said 55 trackway, the said stop member being movable with the aforesaid movable member.

3. In a device of the character described, 60 an actuating member, a movable member associated with said actuating member, a stop carried by said movable member, a second movable member, a latch carried by said second movable member, an abutment carried by said second movable member, a coin trackway positioned to conduct a coin between the said stop and the said abutment, 65 said trackway having a portion which depends below said stop, a plurality of stops associated with said trackway, said stops being located throughout the length of said depending portion of the trackway whereby 70 a suitable stop may be positioned in the trackway to vary the coin receiving depth thereof, said stops being removable as a unit with the aforesaid movable member.

4. In a device of the character described, 75 an actuating member, a movable member associated with said actuating member, a stop carried by said movable member, a second movable member, a latch carried by said second movable member, an abutment carried by the said second movable member, a coin trackway positioned to conduct a coin between the said stop and the said abutment, 80 said trackway having a portion which depends below the position of the stop member and the abutment, a plurality of openings arranged in said trackway and extending throughout the length of the depending portion thereof, a shaft mounted adjacent said trackway, stop members carried by the 85 shaft and positioned to selectively engage with the openings in the trackway, thereby to vary the coin receiving depth of said trackway, and means for positioning the said shaft, said shaft and stops being movable 90 as a unit with the aforesaid movable member.

5. In a device of the character described, 95 an actuating member, said actuating member having a portion which has an annular surface with a notch formed therein, a latch 100 adapted to cooperate with the said portion having the annular surface and normally engaging said notch, a slidible member upon which said latch is mounted, an abutment associated with said movable member, a second movable member, a stop associated with said second movable member, the stop being positioned adjacent the said abutment and adapted to be operatively connected therewith by an interposed coin, a pin carried by 105 the second movable member, a second pin carried by the actuating member, said pins being adapted to engage during a portion of 110 the movement of the actuating member.

In testimony whereof, I hereunto affix my 115 signature.

GEORGE H. MATCHETT.
